CLAY CUTTING DEVICE

Josef Scheibl, Wels, Austria, assignor to Julianna
Orbell, New York, N. Y.

Application January 17, 1938, Serial No. 185,354

8 Claims.

(Cl. 25—105)

This invention relates to improvements in clay cutting devices and relates more specifically to an improved cutter for brick, tile and other similar articles as they emerge in the green or unbaked state from the extruding machine which continuously feeds a strip of clay having the desired transverse formation of the finished article.

The invention relates more particularly to a device for making a transverse cut of predetermined contour in the extruded material, as distinguished from the usual clay cutting devices which are adapted to make the conventional smooth, transverse cut on one plane, which latter machines are employed in the manufacture of common rectangular brick.

In the manufacture of articles from clay and like materials, a wire is normally employed for making the transverse cut since the wire, while not as sharp as a knife, nevertheless has a far lower skin resistance than the knife, while passing through the clay.

One of the principal objects of the present invention is the provision of an improved apparatus for cutting hollow brick of the type described in my co-pending application Serial No. 142,338, although it will be appreciated that the instant invention is in no measure limited to a device for the cutting of such brick or tile, since the device is equally useful for the making of a cut of predetermined contour in any plastic material.

In my aforementioned co-pending application, I described a brick having a plurality of longitudinal apertures extending from end to end, the total transverse area thereof being equal to or greater than the total transverse area of the remaining walls. In some instances, of course, the total area of the voids might be less than the combined area of the solid portions. Difficulty has always been experienced in the cutting off of such brick as distinguished from tile, in that the relatively thin walls break down during the cutting operation, thereby rendering the brick useless.

The cutting of the particular brick described in said application is rendered particularly difficult by virtue of the fact that the transverse cut is not a straight one on a single plane but rather is varied. I provide, for instance, a vertical recess of substantial width adjacent to each vertical edge of the brick, and when two such brick are placed end to end, the mortar is poured into such recesses, the mortar being of such consistency as to slightly enter but not fill the longitudinal apertures.

In order to form brick of this general character, it is necessary to make a double cut as the brick is extruded, since the contour of the meeting terminals of the brick are similar but are in the reverse. Accordingly, I employ a pair of suitably supported wires which are moved in opposite directions and which work against each other, even though the general planes of movement of the two wires are slightly separated. The wire cutters are guided in their course by means of templates or guide plates.

The invention is not limited to a machine for making a double cut, however, since it may be used with good results when the meeting terminals of the brick are of the same contour, in which case only a single cut is made.

The embodiment of the invention illustrated in the drawings is a hand operated device, although it will be appreciated that the machine may be appropriately modified to cause it to be motor driven and substantially automatic in operation.

In said drawings,

Fig. 1 is an isometric view of the cutting machine, the view showing the two wire cutting elements in a substantially intermediate position;

Fig. 2 is similar to Fig. 1 but shows the relationship of the parts when the cutting frames have been drawn to their maximum outward position when the movable carriage has been moved into engagement with the plate 27;

Fig. 3 is a perspective view of the preferred guide plate or template employed in the present machine;

Fig. 4 is a perspective view of a brick, showing the terminal surfaces which are cut by the present machine;

Fig. 5 is a perspective view of another template having only a single recess which is adapted to be used where only a single cut is made;

Fig. 6 is a perspective view of a brick of the type adapted to be cut by the template shown in Fig. 5; and

Fig. 7 is a perspective view of one form of tensioning device for the upper end of the cutting wire.

The presently preferred embodiment of the invention consists of a longitudinal movable frame or carriage 10 comprising a pair of spaced longitudinal angle bars 11 and 12, which bars are secured together in their spaced relationship by means of transverse members 14. Extending downwardly from the angles at each end thereof are brackets 16 carrying shafts 17 upon which rollers 18 are pivotally mounted. The entire frame 11 is supported by these rollers 18 which

ride on suitable trackways 20 and 21, which trackways are provided with suitable vertical supports 22. The outer terminals of these trackways are upwardly turned, as indicated at 24, although any other suitable stop means may be employed at this point. If desired, the wheels 18 may be flanged, or other means may be provided for preventing the same from passing off the trackways.

The particular brick or tile which are adapted to be transversely cut by the present cutting machine are provided with a plurality of longitudinal apertures, thereby making for a lighter brick than if the same were solid. It will be appreciated, however, that the machine is not limited to a device for cutting hollow or substantially hollow brick, but may be employed generally for cutting clay or like materials. Also, the brick which this machine is particularly adapted to cut transversely is of a type which is extruded from an extrusion machine as distinguished from a molded brick. The extrusion machine (not illustrated) is positioned to the left of the movable cutting device, and the extruded material is adapted to pass over a stationary plate, a broken portion of which is indicated at 27, which plate is spaced from the cutting frame when in its outward position indicated in Fig. 1.

Mounted on a plurality of angle brackets 28, which are supported on the upper surfaces of the longitudinal angles 11 and 12, are a pair of substantially rectangular slide plates 30 and 31, which slide plates are positioned on the same plane as the stationary plate 27. When the process begins, the slidable carriage is moved to the left where it comes into engagement with the plate 27, at which time the clay or other material is extruded from the extrusion machine and passes over the plates 30 and 31 until its forward end is stopped by coming into engagement with a stop plate 34 which, when the carriage is in the position shown in Fig. 1, is in a downwardly inclined position.

The stop plate 34 is mounted on another plate 35 provided with bearing portions 36 which are supported on a transverse shaft 37. The shaft 37 is supported adjacent to its terminals in a pair of bearings 38 secured on the upper surface of the angles 11 and 12 adjacent to the outer ends thereof. One end of this shaft extends beyond its bearing and is provided with a crank 40 having a roller 41 on its crank arm 42. The longitudinal trackway 20 supports an upwardly extending bracket 44, the outer vertical edge 45 of which is engaged by the roller 41. Thus, as the carriage is moved to the left, the roller 41 engages this vertical edge 45 and causes the stop plate 34 to assume a vertical position when the extruded material reaches the outer end of the plate 31, thereby stopping its further movement. The cutting device is now ready to function.

The cutting elements are supported on a pair of spaced vertical supports 48 and 49 which are rigidly mounted on opposite sides of the frame. A substantially rectangular template 51 is mounted between the standards 48 and 49 at the upper end thereof, and a pair of bearings 53 and 54 are also mounted at the upper ends of said standards 48 and 49, respectively. Each of the bearing members 53 and 54 are provided with bearing portions 55 and 56 at opposite ends thereof.

On each of the longitudinal angle members 11 and 12, directly below the bearing portions 55 and 56, there are also mounted bearing members 57, which upper and lower bearing members sup-

port a pair of transversely movable frames 60 and 61 which support the cutting elements. These frames comprise vertical end portions 63 and upper and lower transverse rods 64. The vertical arm 63 of the frame 60 is provided with a handle member 66. The two frames 60 and 61 are adapted to be moved simultaneously in opposite directions by the means now to be described, and in the preferred operation of the device, the frame 60 is adapted to begin its movement when it is positioned at its maximum outward location from the movable carriage. When this frame 60 is positioned at its maximum outward position (i. e., when the frame 60 has been drawn outwardly by grasping the handle 66) the frame 61 is in its maximum position in the opposite direction. A pair of pulleys 70 and 71 are mounted on the bearing members 53 and 54, and a cable 73 is secured at one end thereof to the frame 60 at the point 74, and at its opposite end to the frame 61 at the point 75, which cable passes around the pulley 70. Another cable 76 is secured to the opposite side of the frame 60 at the point 77, and its other terminal is secured to the frame 61 at the point 78. Thus it will be appreciated that as the frame 60 is moved in one direction by means of grasping the handle 66, the frame 61 will move in the opposite direction.

The frame 61 supports a stirrup-shaped bracket 80 which is pivotally mounted at 81 and 82 to bearing members 83 and 84. This stirrup-shaped bracket 80 is thus pivotally movable within limits which are restricted by other portions of the device. Another stirrup-shaped bracket 88 is pivotally mounted to the opposite side of the frame 61 at 89 and 90, which bracket likewise is movable within short limits. At the inner terminals of each of the pivotally mounted brackets 80 and 88 are mounted cutting wires 94 and 95 respectively, which wires are secured to blocks 96 at their lower ends and pass over blocks 97 at their upper ends. Suitable tensioning means are provided for these wires, which will be described hereinafter, said tensioning means including a pawl 98, a ratchet 100, and a thumb turn 101. In order to cause the wire to pass over the block more readily, a small roller 102 is provided.

Mounted at the inner end of the brackets 80 and 88 above the wires are a pair of slide rollers 104 and 105, which are adapted to move longitudinally in a pair of irregularly shaped slots 107 in the template 51. In the template shown in Figs. 1, 2 and 3, there are two such longitudinal openings which are formed to correspond with the desired cut at the end of the brick. The two slots are formed in the template when a double cut is desired for the extruded brick. In cases, however, where only a single cut is desired, a single slot in the template is provided and only one of the pivoted stirrup-shaped brackets 80 or 88 is employed. Only one such template is shown in Figs. 1 and 2, which template is positioned above the upper ends of the stirrup-shaped brackets 80 and 88. In cases, however, where the material is quite difficult to cut, a second template should be positioned below the brackets 80 and 88, which template will have longitudinal recesses corresponding to those in the upper template, and in this instance the lower ends of the brackets 80 and 88 are also fitted with rollers similar to the rollers 104 and 105.

From the foregoing, it will be clear that as the extruded material passes over the plates 30 and 31 the wire 94 mounted on the pivoted bracket

et 80 should be in its maximum position to the left of the center of the device, and the wire 95 mounted on the pivoted bracket 88 is in its maximum position to the right of such center, all as shown in Fig. 2. After the extruded material has passed to the outer end of the plate 31 and engages the stop plate 34, and the material is about to be given its double cut, it is desirable that some suitable side supporting means for the material be provided, and to this end there are provided a pair of vertical supports 112 and 113 to which are secured on their inner faces a strip of felt 114. These vertical supports are mounted on horizontal rods 116 which pass through spaced horizontal apertures in the vertical members 48 and 49. At the outer terminals of such rods there are positioned washers 118 and cotter pins 119, and between the members 112 and 48 a spring 121 is concentrically mounted on each rod 116.

Thus, the supporting members 112 and 113 are normally urged inwardly, and in order to retract the members as the material moves over the plates 30 and 31, these members 112 and 113 are formed with upwardly extending portions 123 which are adapted to be engaged by the blocks 97 positioned at the inner terminals of the frames 80 and 88. Thus, when the frames are moved to their maximum outward position prior to the cutting operation, these blocks engage the upwardly extending portions and move the extending portions outwardly.

At the beginning of the cutting operation, the blocks 97 cease their engagement with the portions 123 and the supporting members 112 and 113 and move inwardly to a point where they are in firm engagement with the sides of the material to be cut. The plates 30 and 31 are further formed with longitudinal guide members 125 and 126 which are adapted to guide the material as it passes therover.

In the operation of the device, the movable carriage 10 is moved to the left, wherein it is in meeting engagement with the vertical edge of the plate 27 which forms a part of the extruding machine. In this position the stop plate 34 is in a vertical position, as shown in Fig. 2. The clay (not shown) emerges from the extrusion machine and passes over the plates 30 and 31 until it is in engagement with the stop plate 34. The handle 66 is now manipulated, thereby releasing the vertical supporting plates 112 and 113 in order that they may come into firm engagement with the vertical walls of the brick and the cutting wires 94, 95 pass through the clay. At the end of the stroke, the vertical supports 112 and 113 are again forced out of engagement with the clay and the carriage is moved to the right, thereby lowering the stop plate 34 and permitting the removal of the brick. At the same time, the waste material formed by the two cuts is removed and the carriage is again moved to the left and the extruded clay again forced into engagement with the stop plate 34.

As a hand operated embodiment, the carriage is preferably stationary during the cutting operation, although when the invention is embodied in an automatic or semi-automatic machine, the carriage may be moved to the left and the clay fed onto the plates 30 and 31. In this instance the clay is desirably continuously fed and the cutting operation takes place as the carriage is moving to the right. It will be appreciated that any desired shape of cut may be made by varying the shape of the slots in the templates 51.

The bricks 130 and 131 illustrated in Figs. 4 and 6, respectively, are shown as being solid, although it will be appreciated that the present cutting device finds its greatest usefulness in cutting a brick having one or more longitudinal apertures or voids. The brick shown in Fig. 6 is the result of providing a single cut only by using a template 132 having the single recess or slot 133. The brick 130 is formed with a pair of spaced vertical recesses 136 adjacent to each vertical edge thereof, and when two such bricks are laid in end to end relationship, a substantial double recess is formed into which the mortar may be poured, all as described in my copending application. The brick 131 is formed with recesses or female portions 138 at one end thereof and with corresponding male portions 139 at opposite ends, which brick is also useful for many purposes.

Fig. 7 illustrates one form of tensioning device for the cutting wire previously described. In this instance the block 97 is suitably mounted on the pivoted frame and a pin or roller 102 is positioned at one end thereof. The wire 95 passes over this roller and is secured to a shaft 140 having a thumb turn 101. A ratchet wheel 100 is keyed to this shaft and when the proper tension of the wire has been secured, the ratchet is engaged by a pawl 99 which is provided with a finger engaging portion 141 at the opposite end thereof. The ratchet portion is downwardly engaged by means of a spring 142 supported by a pin 143. It will be appreciated that this tensioning device may be modified considerably without departing from the invention.

What I claim is:

1. A device for making transverse cuts in extruded plastic material comprising a base member for receiving such material as it leaves the extrusion die, a movable carriage supporting said base member and adapted to travel with the extruded material during the cutting operation, a pair of spaced frames movable transversely of the base member, and means for supporting said frames on said carriage, a cutting element support pivotally mounted at one end on each frame, a cutting element comprising a wire mounted on the other end of each support, and means for guiding such other end of the support during transverse movement to cause the cutting element to make a cut of predetermined contour.

2. A device for making a plurality of closely spaced transverse cuts in extruded plastic material to form complementary recesses in the end walls of blocks made from such material, such device comprising a base member for receiving such material as it leaves the extrusion die, a movable carriage supporting such base member and adapted to travel with the extruded material during the cutting operation, a pair of cutting wires movable transversely of the carriage and adapted to travel through the moving extruded material in closely spaced planes, means for supporting said wires on said carriage and comprising a pair of spaced frames movable transversely of the base, and means for supporting said frames on said carriage, a cutting wire support pivotally mounted at one end thereof on each frame, means at the other end of each support for supporting the wire in taut condition, means for guiding such other end of the support during transverse movement to cause the cutting wire to make a cut of predetermined contour, and means for causing one frame to move in one

direction when the other frame is moved in the opposite direction.

3. A machine for making a plurality of closely spaced transverse cuts in extruded plastic material and forming complementary recesses in adjacent blocks of such material, such machine comprising a base member for receiving such material as it leaves an extrusion die, a longitudinally reciprocating carriage supporting said base member and adapted to travel with the extruded material during the cutting operation, a pair of spaced frames movable transversely of the base member, means for supporting said frames on said carriage, a cutting element support pivotally mounted at one end on each frame, a cutting element comprising a wire mounted on the other end of each support, means for guiding such other end of each support during transverse movement, and means for gauging the length of the blocks to be cut comprising a stop member at the rear end of the base member, a transverse shaft supporting such stop member, means for causing such stop member to assume a vertical position when the base member is in forward position, and means for lowering the stop member when the base member is in rearward position.

4. A device for making transverse cuts in extruded plastic material comprising a base member for receiving such material as it leaves the extrusion die, a support positioned on each side of the base member, a pair of spaced reciprocating frames journaled in each of said supports and being movable transversely of the base member, a substantially U shaped cutting element support 35 journaled at its outer end adjacent the outer terminal of each frame, a cutting element comprising a wire mounted between the inner terminals of each support, means for guiding such inner terminal of each support during transverse movement to cause the cutting element to make a transverse cut of predetermined contour, such means comprising a template having an elongated recess corresponding to said contour, and guiding means carried by each cutting element support adapted to travel in such recess.

5. A device for making transverse cuts in extruded plastic material comprising a base member for receiving such material as it leaves an extrusion die, a reciprocating carriage supporting said base member and adapted to travel in the direction of movement of the extruded material during the cutting operation, a vertical support positioned on each side of the base member substantially midway between each end thereof, a pair of transversely movable cutting elements, each element comprising a frame journaled in said supports, a cutting element support pivotally mounted at its outer end adjacent to the outer end of each frame, a cutting wire mounted between the inner ends of each support, means for guiding such inner ends of each support during transverse movement to cause the cutting element to make a cut of predetermined contour, such means comprising a

a cam follower carried by said support adapted to engage the cam surface.

6. A device for making transverse cuts in extruded plastic material comprising a base member for receiving such material as it leaves the extrusion die, a reciprocating carriage supporting said base member and adapted to travel with the extruded material during the cutting operation, a vertical support positioned on each side of the base member substantially midway between each end thereof, a pair of spaced reciprocating frames journaled in said supports and being movable transversely of the base member, a substantially U shaped support pivotally mounted at its outer end adjacent to the outer end of each frame, a cutting element comprising a wire mounted between the inner ends of each support, means for guiding such inner ends of the supports during transverse movement to cause the cutting element to make a cut of predetermined contour, such means comprising a template having an elongated recess corresponding to said contour, guiding means carried by said support movable in such recess, and means for causing the frames to simultaneously move in opposite directions.

7. A device for making transverse cuts in extruded plastic material comprising a base member for receiving such material as it leaves the extrusion die, a reciprocating carriage supporting said base member and adapted to travel with the extruded material during the cutting operation, a vertical support positioned on each side of the base member, a pair of spaced reciprocating frames journaled in said supports and being movable transversely of the base, a support pivotally mounted at one end on each frame, a cutting element comprising a wire mounted between the terminals of the other end of each support, means for guiding such inner terminals of the support during transverse movement to cause the cutting element to make a cut of predetermined contour, and means for supporting the side walls of the plastic material during the cutting operation comprising a retractable member which engages each side wall of the extruded material, and means carried by the frame for retracting such members.

8. A device for making a transverse cut of predetermined contour in extruded plastic material comprising a base member for receiving such material as it leaves the extrusion die, a movable carriage supporting such base member and adapted to travel with the extruded material during the cutting operation, a frame movable transversely of the base member and means on such base member for supporting said frame, a substantially U shaped cutting element support pivotally mounted at one end on each frame, a cutting element comprising a wire mounted on the other end of each support, and means for guiding such other end of the support during transverse movement to cause the cutting element to make a cut of predetermined contour.

JOSEF SCHEIBL.
